UNITED STATES PATENT OFFICE.

CHARLES H. WILLIAMS, JR., OF CHICAGO, ILLINOIS, ASSIGNOR TO CHICAGO RAILWAY EQUIPMENT COMPANY, OF CHICAGO, ILLINOIS, A CORPORATION OF ILLINOIS.

SIDE BEARING.

SPECIFICATION forming part of Letters Patent No. 712,224, dated October 28, 1902.

Application filed March 31, 1902. Serial No. 100,731. (No model.)

To all whom it may concern:

Be it known that I, CHARLES H. WILLIAMS, Jr., a citizen of the United States, residing at Chicago, county of Cook, State of Illinois, have 5 invented a certain new and useful Improvement in Side Bearings, of which the following is a full, clear, and exact description, such as will enable others skilled in the art to which it appertains to make and use the same, reference being had to the accompanying drawings, forming part of this specification, in which—

Figure 1 is a sectional view through my improved side bearing; and Fig. 2 is a sectional view on line 2 2, Fig. 1.

This invention relates to a new and useful improvement in side bearings, the object being to simplify the construction of antifriction-bearings of the character described and 20 at the same time reduce the cost of manufacture of said bearings to a minimum.

With these objects in view my invention consists in the construction, arrangement, and combination of the several parts, all as 25 will hereinafter be described, and afterward pointed out in the claims.

In the drawings, 1 indicates a casting provided with the usual perforated lugs 2 for the passage of securing-bolts. This casting 30 receives a cap 3 at its upper end, said cap being secured in position by appropriate means and forming, with the casting 1, a bearing for the antifriction-rollers 4 and 5. These antifriction-rollers, as shown, preferably have 35 coned faces to accommodate the movement of the body-bearing, the cone of said faces being determined by the distance of the side bearing from the king-pin of the truck. As the rollers in operation travel at different circumferential speeds and as in service but one 40 of said rollers might be in operation while the other remains idle, I prefer to divide the axle of spindle 6, on which they are mounted, and form heads 7 on the inner contiguous 45 ends of said parts of the spindle, said heads being received and operating in an enlarged chamber formed by the cap-piece and casting 1.

I am aware that many minor changes in 50 the construction, arrangement, and combination of the several parts of my device can be made and substituted for those herein shown

and described without in the least departing from the nature and principle of my invention.

Having thus described my invention, what I claim as new, and desire to secure by Letters Patent, is—

1. In a side bearing for railway-cars, the combination with a bearing, of a divided 60 spindle journaled therein, and rollers arranged on the ends of said divided spindle; substantially as described.

2. In a side bearing for railway-cars, the combination of a bearing, of a divided spindle, 65 and coned rollers on said spindle at each side of said bearing; substantially as described.

3. In a side bearing for railway-cars, the combination with a bearing, and coned rollers arranged on each side thereof and whose 70 axes of rotation are coincident; substantially as described.

4. In a side bearing for railway-cars, the combination with a bearing, a divided spindle mounted in said bearing, coned rollers arranged on the ends of said spindle on each side of said bearing, and a cap-piece on the bearing for holding the spindle in place; substantially as described.

5. In a side bearing for railway-cars, the 80 combination with a bearing, of a cap-piece, a divided spindle journaled in said bearing, rollers on the outer ends of said spindle, and heads on the adjacent ends of said divided spindle; substantially as described.

6. In a side bearing for cars, the combination with a bearing, and rollers of different diameters mounted on each side thereof and capable of independent rotation; substantially as described.

7. In a side bearing for cars, the combination with a bearing, of a divided spindle mounted therein, and rollers on the outer ends of said spindles whereby said rollers are capable of independent rotation; substantially as described.

In testimony whereof I hereunto affix my signature, in the presence of two witnesses, this 24th day of March, 1902.

CHARLES H. WILLIAMS, JR.
